PATENTED JULY 17, 1906.

H. TERRY.

PUMP.

APPLICATION FILED SEPT. 13, 1905.

UNITED STATES PATENT OFFICE.

HIRAM TERRY, OF HEREFORD, TEXAS.

PUMP.

No. 826,071.

Specification of Letters Patent.

Patented July 17, 1906.

Application filed September 13, 1905. Serial No. 278,312.

To all whom it may concern:

Be it known that I, HIRAM TERRY, a citizen of the United States, residing at Hereford, in the county of Deaf Smith and State of 5 Texas, have invented a new and useful Pump, of which the following is a specification.

This invention relates to pumps, and has for its object to provide a novel construction and arrangement of parts whereby the operating mechanism of the pump is effectually balanced in a simple and convenient manner, so as to require comparatively slight power to manipulate the same.

A further object of the invention is to materially simplify the valve mechanism of the pump and to enable convenient access thereto for repacking the same when worn.

With these and other objects in view the present invention consists in the combination 20 and arrangement of parts, as will be herein-after more fully described, shown in the accompanying drawings, and particularly pointed out in the appended claims, it being understood that changes in the form, proportion, size, and minor details may be made 25 within the scope of the claims without departing from the spirit or sacrificing any of the advantages of the invention.

In the accompanying drawings, Figure 1 is 30 an elevation, partly in section, of a pump constructed in accordance with the present invention and arranged for use in a dug well. Fig. 2 is a similar view showing the invention arranged for use in a bored well. Fig. 3 is a 35 detail sectional view on the line 3 3 of Fig. 1.

Like characters of reference designate corresponding parts in each figure of the drawings.

In the embodiment of the invention as 40 shown in Fig. 1 a suitable platform 1 is supported across the top of the well 2, and a post or standard 3 is erected centrally upon the platform. Upon the top of the post or standard 3 there is fulcrumed a walking-beam 4, 45 from one end of which depends a pump-rod 5, passing through a suitable opening 6 in the platform and provided upon its lower end with a submerged plunger 7. This plunger works in a stationary submerged upright cylinder 8, which is rigidly connected to a suitable support—for instance, an upright rod or bar 9, having its lower end seated in the bottom of the well and its upper end connected to the platform 1, any approved form of 55 brackets 10 being employed to connect the cylinder to the supporting-rod. The cylin-

der 8 is open at its top and closed at its bottom and provided therein with an outlet-port 11, from which leads downwardly an outlet-pipe 12. A downwardly-opening foot-valve 60 13 is provided for the port 11, and the plunger 7 is also provided with a downwardly-opening valve 14, whereby water is taken into the cylinder upon the upward stroke of the plunger and discharged through the port 65 11 upon the downward stroke of the plunger. An upright discharge-pipe 15 is hung from the opposite end of the walking-beam, preferably by having its downturned elbowed upper terminal 16 received within a bail-shaped link or hanger 17, pivotally swung from the walking-beam. This discharge-pipe 15 works vertically through an opening 18 in the platform 1 and at its lower end is provided with a substantially horizontal branch 70 19, which is connected to the lower end of the outlet-pipe 12 by a hinged joint 20 to permit of the necessary up-and-down movement of the pipes 15 and 19. To balance the weight of the pipe 15 and the water therein, a suitable counterbalancing-weight 21 is carried by the pump-rod 5, said weight preferably being made up of a series of weights of different sizes, which are slipped down upon the rod and supported thereon within the well above 75 80 85 the level of the water.

In the operation of the pump power is applied in any suitable manner to the walking-beam so as to reciprocate the same in a vertical direction. Upon the downward movement of the plunger the water in the cylinder will be forced downwardly through the pipe 12, thence through the pipe 19, the upright pipe 15, and finally out through the discharge spout or elbow 16. During the upward stroke of the plunger the plunger-valve 14 will of course open, and the water in the well will pass downwardly through the open top of the cylinder, the foot-valve 13 of course being held in its closed position by the 90 weight of the column of water in the discharge-pipe 15. As the plunger-rod and the plunger are effectually balanced by hanging the discharge-pipe 15 from the walking-beam, the power required to operate the pump is 95 only enough to overcome the weight of the column of water in the discharge-pipe, wherefore a comparatively small power is required for the operation of the present pump, and the working of the device is smooth and regular. 100 105 110

While the arrangement shown in Fig. 1 is

satisfactory for a dug well, the discharge-pipe and the plunger-rod are too far apart for use in a bored well, wherefore I have provided the arrangement shown in Fig. 2 to accommodate the pump to a bored well. In the latter arrangement the same form of platform 1 is provided across the top of the bored well 22, there being the same form of standard or post 13 erected upon the platform, with the walking-beam 4 fulcrumed upon the top thereof. Beneath the walking-beam there is a substantially horizontal stationary cross-head 22, fixed to the post or standard, and upon the opposite ends of the cross-head are mounted the vertically-swinging levers 23 and 24, which are fulcrumed midway of their ends, as shown at 25 and 26. A connecting-link 27 extends between the outer end of the lever 23 and the adjacent end of the walking-beam, while another link 28 extends between the outer end of the lever 24 and the adjacent end of the walking-beam. The pump-rod 5 is hung from the inner end of one of the levers, (here shown as the lever 23,) and the upright discharge-pipe 15 is hung from the inner end of the lever 24 by means of the hanger 17. The lower end of the pump-rod has the plunger 7, which works in the cylinder 8, and is also equipped with the downward-opening valve 14. The outlet-pipe 12 leads downwardly from the outlet-port 11 in the bottom of the cylinder and is provided at its lower end with the substantially horizontal branch pipe 29, rigidly secured thereto. The lower end of the pipe 15 is terminated short of the pipe 29, and a flexible tube or pipe 30 communicates with the upturned elbowed terminal 31 of the pipe 29 and the lower end of the discharge-pipe 15, the intermediate portion of this flexible pipe being arranged in a coil, so as not to interfere with the up-and-down movement of the pipe 15. By this arrangement of parts the pump-rod 5 and the discharge-pipe 15 are brought sufficiently close together to be received within the bored well, while the operation of the device is substantially the same as that described for the form shown in Fig. 1 of the drawings, with the exception that the plunger is elevated by the downward movement of the adjacent end of the walking-beam, which is brought about by the interposition of the lever 23 and the link 27 between the plunger-rod and the walking-beam.

From the foregoing description it will be understood that the pump of the present invention is effectually balanced in a very simple manner by hanging the weighted plunger-rod and the discharge-pipe from opposite ends of the walking-beam employed to impart the desired reciprocatory movements to the pump-rod, whereby certain elements of the pump are employed to counterbalance one another, and therefore extraneous balancing means are dispensed with. More-

over, the valve mechanism of the pump is materially simplified, as only two valves are required, one for the plunger and one at the foot of the cylinder. The foot-valve 13 is at no time under great pressure and merely opens and closes with the movement of the water, and therefore is not liable to get out of order, while the plunger-valve 14 is conveniently accessible by disconnecting the plunger-rod from the walking-beam and drawing said rod upwardly until the plunger can be reached for repacking the valve. The parts of the present apparatus are reduced to the minimum without in any manner detracting from its effectiveness, and by reason of the balancing of the parts only a comparatively small power is required for operating the pump.

As a further aid to the easy running and manipulation of the pump each form thereof is provided with a weight 32, which in the horizontal position of the walking-beam is located centrally above the fulcrum of the beam and is supported by oppositely-extending arms 33, which have their outer ends secured to the walking-beam at opposite sides of the fulcrum thereof. When the weight 32 is rocked to either side of the fulcrum of the walking-beam, it will aid in depressing one or the other of the elements 5 and 15. By preference each arm 33 has a hinge or pivotal connection with one end of the weight 32, and its other end has a detachable pivotal connection with one of a series of perforations 34, formed in a walking-beam, whereby the weight 32 may be adjusted vertically, so as to vary the leverage thereof to suit the conditions of the pump.

Having fully described the invention, what is claimed is—

1. In a pump, the combination with a walking-beam, of a submerged stationary cylinder, a vertically-movable discharge-pipe having a flexible connection with the discharge-port of the cylinder, a plunger-rod having a plunger working in the cylinder, and operative connections between the plunger-rod and one end of the walking-beam and between the discharge-pipe and the other end of the walking-beam for counterbalancing the plunger-rod by the discharge-pipe.

2. In a pump, the combination with a walking-beam and a stationary submerged cylinder, of a plunger-rod connected to and actuated by one end of the walking-beam, a plunger carried by the plunger-rod and working in the cylinder, a vertically-movable discharge-pipe connected to and actuated by the other end of the walking-beam, and a flexible connection between the discharge-pipe and the discharge-port of the cylinder, the plunger-rod being weighted to counterbalance the discharge-pipe.

3. In a pump, the combination of a stationary submerged cylinder, a walking-beam,

- a plunger-rod actuated by one end of the walking-beam and provided with a plunger working in the cylinder, an endwise-movable discharge-pipe actuated by the other end of the walking-beam, and a flexible pipe connecting the discharge-pipe with the outlet-port of the cylinder and exceeding in length the maximum space between the discharge-pipe and the cylinder to permit of endwise movement of the discharge-pipe.
4. In a pump, the combination of a walking-beam, a stationary submerged cylinder, a plunger-rod actuated by one end of the walking-beam, and provided with a plunger working in the cylinder, an endwise movable discharge-pipe actuated by the other end of the walking-beam, and a flexible coiled pipe connecting the discharge of the cylinder with the discharge-pipe, the length of the coil exceeding the maximum space between the cylinder and the discharge-pipe.
5. In a pump, the combination of a walking-beam, a stationary cylinder, a pair of levers fulcrumed independently of the walking-beam, connections between the levers and the respective ends of the walking-beam, a plunger-rod hung from one of the levers and provided with a plunger working in the cylinder, a discharge-pipe hung from the other lever, and a flexible connection between the cylinder and the discharge-pipe, the plunger-rod and the discharge-pipe being counterbalanced.
6. In a pump, the combination of a support, a walking-beam fulcrumed thereon, a cross-head fixed to the support, levers intermediately fulcrumed upon opposite end portions of the cross-head, links connecting the levers with the walking-beam, a plunger-rod hung from one of the levers and provided with a plunger, a submerged stationary cylinder in which the plunger works, a discharge-pipe hung from the other lever, and a flexible connection between the cylinder and the discharge-pipe.
7. In a pump, the combination of a walking-beam, levers fulcrumed intermediate of their ends at opposite sides of the fulcrum of the walking-beam and independently of the latter, links connecting the outer ends of the levers with the respective ends of the walking-beam, a plunger-rod hung from the inner end of one of the levers and provided with a plunger, a stationary submerged cylinder in which the plunger works, a discharge-pipe hung from the inner end of the other lever, and a flexible connection between the discharge-pipe and the cylinder, the plunger-

rod and the discharge-pipe being counterbalanced.

8. In a pump, the combination with a walking-beam, of a submerged cylinder, a vertically-movable discharge-pipe hung from the walking-beam and connected to the cylinder, a plunger-rod hung from the other end of the walking-beam and provided with a plunger working in the cylinder, the discharge-pipe and the plunger-rod being counterbalanced, and a weight carried by the walking-beam and supported vertically above the fulcrum thereof in the horizontal position of the beam.

9. In a pump, the combination with a walking-beam, of a submerged cylinder, a vertically-movable discharge-pipe hung from one end of the walking-beam and connected with the cylinder, a plunger-rod hung from the other end of the walking-beam and provided with a plunger working in the cylinder, the discharge-pipe and the plunger-rod being counterbalanced, and a vertically-adjustable weight carried by the walking-beam and located vertically above the fulcrum thereof in the horizontal position of the beam.

10. In a pump, the combination with a walking-beam, of a submerged cylinder, a discharge-pipe hung from one end of the walking-beam and connected to the cylinder, a plunger-rod hung from the other end of the walking-beam and provided with a plunger working in the cylinder, a discharge-pipe and the plunger-rod being counterbalanced, a weight disposed centrally above the walking-beam, and supporting-arms connected to the weight and to the walking-beam at opposite sides of its fulcrum.

11. In a pump, the combination with a walking-beam, of a submerged cylinder, a discharge-pipe hung from one end of the walking-beam and connected to the cylinder, a plunger-rod hung from the other end of the walking-beam and provided with a plunger working in the cylinder, the discharge-pipe and the plunger-rod being counterbalanced, a weight disposed centrally above the walking-beam, and weight-supporting arms having their lower ends connected to the walking-beam at opposite sides of its fulcrum and adjustable longitudinally thereon to raise and lower the weight.

In testimony that I claim the foregoing as my own I have hereto affixed my signature in the presence of two witnesses.

HIRAM TERRY.
